UNITED STATES PATENT OFFICE.

THOMAS JOHN DISTURNAL, OF BELMONT, IRELAND.

CARBURETER.

1,205,602.

Specification of Letters Patent. Patented Nov. 21, 1916.

Application filed January 11, 1916. Serial No. 71,497.

To all whom it may concern:

Be it known that I, THOMAS JOHN DISTURNAL, a subject of His Majesty the King of England, residing at Belmont, in the county of Kings, Ireland, have invented certain new and useful Improvements in Carbureters for Internal-Combustion Engines, of which the following is a specification.

10 This invention relates to improvements in carbureters for internal combustion engines.

The object of the invention is to provide a carbureter by means of which the consumption of fuel is greatly economized when working at varying loads, a perfect explosive mixture can be obtained under all conditions of working of the engine, and the ratio of the throttle opening can be 20 adjusted to suit the different requirements in accordance with the ratio of the choke tube area, all in improved manner.

The improved carbureter constructed according to the present invention is fitted 25 with two coöperating ported sleeves or cups, one or more choke tubes, each having a free fuel supply nozzle coöperating therewith, and a separate choke tube control valve mounted upon the tube or tubes, said 30 sleeves or cups serving as the main throttle valve of the carbureter, and said control valve serving for varying the effective area of the choke tube or tubes, said throttle valve sleeves or cups and said choke tube 35 control valve being adapted to coöperate with one another to control the explosive mixture passing from the carbureter to the engine.

A suitable manner of carrying out the 40 invention is hereinafter described with reference to the accompanying drawings in which:—

Figure 1 is a part sectional elevation of the complete carbureter. Fig. 2 is an elevation of same, and Fig. 3 a plan of the carbureter showing the upper portion of the casing removed. Figs. 4 and 5 are plan views of the choke tube block and the choke tube control valve respectively. Figs. 6 and 50 7 are partly sectional elevations of the outer and inner throttle valve sleeves or cups, respectively, showing said sleeves or cups as if spread out.

A plurality of fuel nozzles *a* are disposed within a cylindrical or other suitably shaped casing *b* into which cold atmos-

pheric air and / or hot air, or, if desired, air under pressure may be admitted through one or more suitable ports *c*, it being understood that these ports may be valve controlled if desired, and a corresponding number of choke or carbureting tubes *d* are positioned above and around the nozzles and also within the casing. The nozzles *a* are preferably fitted on a common two-part fuel supply chamber *e*, one part *f* of which chamber forms the bottom of the carbureter casing while the other *g* is removably secured thereto, and the choke or carbureting tubes *d* are preferably formed by shaped holes or passages provided in a solid and separate aluminum or other metal plate, block *h* removably secured within said casing by means of a set screw *h'* and packed by an india rubber, cork or like ring *h''*.

A flat disk or plate valve *i* slotted at *i'* is mounted within the casing *b* and immediately on the choke tubes *d* so as to leave no air space between said valve and the tubes, and is adapted to be turned in its own plane to control communication between the tubes and the throttle valve and engine.

The nozzles *a* are arranged in a circular series, and the choke tubes *d* are preferably graduated in size and so arranged that the pilot nozzle *a'* and the smallest tube *d'* are opened first by the movement of the disk valve *i* and so on to the largest throughout the series. The pilot tube and nozzle would be entirely cut out before the last and largest tube and nozzle are fully opened.

Two coöperating main throttle sleeves or cups *j* and *k* are disposed between the choke tube control valve *i* and the induction pipe of the engine, and are adapted to be operated in conjunction therewith to vary and regulate the explosive mixture at will according to the requirements of the engine.

The two sleeves or cups *j* and *k* are fitted one within the other, and the outer sleeve is formed with two or more opposed elongated half diamond or other suitably shaped holes or ports *j'* in its walls, and the inner sleeve with similar ports *k'*. The top or open end of the outer sleeve or cup *j* is an air tight but working fit in a pipe *l* adapted for connection to the induction pipe of the engine, while the inner sleeve or cup *k* is an air tight but working fit in said outer sleeve or cup. A hollow stem or tube *m* is formed or fitted on the closed end of the outer sleeve *j* and is extended outside of the car-

bureter casing and fitted with a manually operated lever *n*, and a spindle *o* formed or fitted on the closed end of the inner sleeve, extends through said hollow stem or tube 5 and is fitted with a similar operating lever *p*. It will be understood that the lever *n* may be automatically operated if desired.

The portion of the stem or tube *m* situated immediately beneath the outer sleeve 10 or cup *j* is fitted with two pins or other projections *q* which are adapted to operate the choke tube control valve *i* and are made a fairly loose fit within suitably shaped slots *r* formed in said valve, so that the pins or 15 projections allow the outer throttle sleeve or cup *j* a lead in its movements in either direction before moving the control valve *i*. The object of this arrangement is that when the outer sleeve *j* is turned a little to open 20 the two ports *k'* formed in the inner sleeve *k*, the opened portions of the ports are increased in area before the exposed area of the choke tubes *d* is altered, and again, when said outer sleeve is being closed, the ports 25 are reduced in area before the exposed area of the choke tubes is reduced, thus by varying the ratio of areas, adding greatly to the acceleration and flexibility of the engine, at the same time causing considerable economy 30 in fuel consumption when the engine is working at varying loads. When the inner sleeve or cup *k* is turned within the outer sleeve *j* by medium of its spindle *o* and lever *p*, the half diamond or other ports *k'* 35 therein can be brought into registration with the ports formed in the outer sleeve or cup, thus fully opening the throttle, and if it is turned in the opposite direction the ports can be fully closed. Also if the inner 40 sleeve or cup *k* is held rigid and the outer sleeve or cup *j* turned thereon by medium of its stem or tube *m* and lever *n*, the half diamond or other ports therein can likewise be either fully opened or fully closed. When 45 the valves *i*, *j* and *k* are fully closed the pilot jet *a'* and the tube *d'* remain uncovered as shown in Fig. 4, thus providing an initial opening to the engine.

The arrangement of a slotted plate such 50 as *i* mounted immediately upon the top of the choke tubes without the addition of the two sleeve valves *j* and *k* would be practically ideal for starting an engine, running 55 dead slow and gaining or maintaining speed, but if it is required to reduce speed quickly and frequently, this arrangement is not sufficient, as by closing said choke tubes by turning said slotted plate back to its original position the suction upon the small 60 choke tube *d'* and pilot jet *a'* left uncovered would be terrific, until the engine has slowed down, thus causing waste of petrol during the said slowing down. To entirely eliminate this disadvantage the double sleeve 65 valve *j*—*k* is employed.

The larger or outer sleeve *j* is really the main throttle for the engine, and is so arranged that it alone, in its movements, controls and actuates the slotted plate *i*, but it is given a lead in its movements in both directions before moving said plate as above described. Thus it will readily be seen that by closing this throttle sleeve the engine suction is retarded on the choke tube area before said sleeve begins to turn the slotted plate which covers the choke tubes and the sleeve is completely shut excepting for the pin prick hole *s* by the time it has closed the slotted plate over the four larger choke tubes *d*; thus the mixture is kept economical 70 in the slowing down of the engine. The lead movement is calculated and fixed when tuning a carbureter up to suit any particular engine it may be fitted to, and the size of the small pin prick hole *s* formed in the 75 wall of the inner sleeve *k* also depends upon engine requirements. This pin prick hole is provided to allow a very small amount of the mixture to pass when the throttle is fully closed, so as not to stop the engine 80 completely in traffic, and to obviate the racing of the engine when starting. It is placed in any part of the wall of the inner sleeve *k* which may be opposite one of the outer sleeve ports *j'* when the throttle is in 85 closed position. The lead movement of the throttle sleeve *j* also has the advantage of obviating the retardation of suction on the earlier choke tubes in the converse or opening-up operation. The object of the inner 90 sleeve or cup *k* is to give complete control over the regulating of the mixture as desired, according to the warming up of the engine and other requirements. The ports *k'* are opened and closed according as the 95 outer sleeve *j* is turned, the inner sleeve being held rigid by its own separate control. By turning the inner sleeve slightly by its 100 control, the size of the ports *k'* can be made larger or smaller as desired. When and as 105 desired, after the engine has warmed up to its work, the inner sleeve or cup can be turned a little so that the ratio of the area of the ports may be reduced to any required 110 extent in comparison to the exposed or subsequently exposed area of the choke tubes, and this reduction in the ratio is maintained 115 constant so long as the inner sleeve is kept rigid at any desired position, no matter what way the outer sleeve is moved. This really 120 means that after running some time and the engine is warm, there is by this arrangement, a larger choke tube area exposed to the suction to give the same volume of the mixture to the engine; as by opening the 125 ports to admit a certain volume of the mixture there is a larger choke tube area exposed than there was previously, which naturally means a weaker mixture this being the chief desideratum after an engine is hot. 130

What I claim is:—

1. A carbureter comprising a casing, fuel supply nozzles, carbureting tubes to coöperate with the nozzles, means adapted to cover and uncover said tubes, and two sleeves adapted to coöperate with each other and with said means to control the carbureted air.
2. A carbureter comprising a casing, fuel supply nozzles, carbureting tubes to coöperate with said nozzles, a plate adapted to be actuated to cover and uncover said tubes, and two sleeves mounted one within the other and adapted to be actuated independently or simultaneously to coöperate with each other and with said plate to control the carbureted air.
3. A carbureter comprising a casing, fuel supply nozzles, carbureting tubes to coöperate with said nozzles, a slotted plate mounted immediately upon said tubes and adapted to be turned in its own plane to cover and uncover said tubes, and two coöperating ported sleeves mounted above said plate and one within the other and adapted to be turned axially independently or simultaneously to coöperate with said plate to control the carbureted air.
4. A carbureter comprising a casing, fuel supply nozzles, carbureting tubes to coöperate with said nozzles, a disk or plate adapted to be actuated to cover and uncover said tubes, two sleeves adapted to be actuated to coöperate with each other and with said plate to control the carbureted air, and an operative connection between one of said sleeves and the plate whereby when said sleeve is actuated it also actuates the plate.
5. A carbureter comprising a casing, fuel supply nozzles, carbureting tubes to coöperate with said nozzles, a plate adapted to be actuated to cover and uncover said tubes, two sleeves adapted to be actuated to coöperate with each other, and with said plate to control the carbureted air, and means operatively connecting one of said sleeves with the

plate and permitting of lost-motion between same, whereby said sleeve is given a lead in its movements, and whereby when it is actuated, and the lost motion has been taken up, 50 the plate is also actuated.

6. A carbureter comprising a casing, fuel supply nozzles, carbureting tubes to coöperate with said nozzles, a slotted plate adapted to be actuated to cover and uncover said tubes, and two ported sleeves adapted to coöperate with one another and with said plate to control the carbureted air, the slots in the plate and the ports in the sleeves being of such sizes and arrangement that the carbureter is provided with an initial opening to the engine when the plate and the sleeves are in their closed positions.

7. A carbureter, comprising a casing, fuel supply nozzles, carbureting tubes to coöperate with the nozzles, means adapted to be actuated to cover and uncover said tubes, two sleeves mounted one within the other, a hollow stem or tube on the outer sleeve and extending exteriorly of the casing, a spindle 70 on the inner sleeve and extending through the stem of the outer sleeve to the exterior of the casing and means connected with the exterior ends of said stem and said spindle whereby the two sleeves can be actuated independently or simultaneously.

8. A carbureter, comprising a casing, fuel supply nozzles, carbureting tubes to coöperate with said nozzles, a plate adapted to cover and uncover said tubes, two sleeves 80 mounted one within the other and within the casing, an operative connection between the outer sleeve and the plate and means whereby said sleeves can be actuated independently or simultaneously and the plate 85 be actuated with said outer sleeve to coöperate with each other to control the carbureted air.

In testimony whereof I have hereunto signed my name to this specification.

THOMAS JOHN DISTURNAL.
